THE NORRIS PETERS CO., PHOTO-LITHO., WASHINGTON, D. C.

UNITED STATES PATENT OFFICE.

FRED MITCHELL STACY, OF PORTSMOUTH, NEW HAMPSHIRE.

MUSIC HOLDER AND TURNER.

SPECIFICATION forming part of Letters Patent No. 569,726, dated October 20, 1896.

Application filed April 11, 1896. Serial No. 587,158. (No model.)

To all whom it may concern:

Be it known that I, FRED MITCHELL STACY, a citizen of the United States, and a resident of Portsmouth, in the county of Rockingham 5 and State of New Hampshire, have invented certain new and useful Improvements in Music Holders and Turners, of which the following is a specification, reference being had to the accompanying drawings, forming a part 10 thereof, in which similar letters of reference indicate corresponding parts.

This invention relates to music holders and turners; and the object thereof is to provide an improved device of this class which is simple in construction and operation and which 15 is adapted to be mounted on a stand, piano, or other instrument and to be used for turning sheet-music or to be connected with a music-book and used for turning the leaves 20 thereof.

The invention is fully disclosed in the following specification, of which the accompanying drawings form a part, in which—

Figure 1 is a plan view of my improved music holder and turner; Fig. 2, a front view thereof; Fig. 3, a section on the line 3 3, and Fig. 4 a section on the line 4 4.

In the practice of my invention I provide a base or support A, which may be composed of 25 any desired material and finished in any desired manner, and the base A is provided with a vertical standard B, on which is mounted a yoke b, through the edge of which passes a set-screw b², by means of which the yoke may 30 be secured to the standard B at any desired point.

Secured to the sides of the yoke b is an angular rod D, having a depending end d, by 40 which it is secured to said yoke, and being provided at its outer end with an upwardly-directed arm d², and secured to the outer end of said rod or in the angle formed by the arm d² is a rod E, which extends parallel with the base A, and to the outer ends of which are 45 secured two semicircular outwardly-curved rods E², and the rod E is provided with ordinary spring-clamps F, which are secured thereto and which are suspended therefrom, and which are designed for use in connecting the 50 music holder and turner with a music-book, or which may be employed for suspending or holding sheets of music.

Mounted on the upwardly-directed arm d² of the rod D is a disk G, above which is mounted an arm g, having a circular head g², and 55 above the circular head g² of the arm g is a spiral spring g³, one end of which is secured to the arm g and the other to a standard g⁴, which is connected with the rod D, and above the spring g³ is another arm, g⁵, above which 60 is placed a spring g⁶, one end of which is secured to said arm g⁵ and the other to the standard g⁴.

The arm g⁵ is curved downwardly, as shown at g⁸, and extends parallel with the arm g, 65 and said arms are both free to swing on the arm d² of the rod D between the curved or semicircular rods E², and the object of the springs g³ and g⁶ is to throw said arms g and g⁵ to the left or into the position occupied by 70 the arm g in Figs. 1 and 2. The outer ends of each of these arms g and g⁵ are provided with spring-clamps L, and pivotally connected with the upper curved rod E², and at the right-hand side or end thereof, is a lever M, 75 the inner end of which is provided with a hook m, and the outer end of which is provided with a depending cord or similar device m², and the outer end of said lever M is also connected with a spring m³, one end of 80 which is secured to the cross-rod E, as shown in Fig. 1.

The operation will be readily understood from the foregoing description, when taken in connection with the accompanying drawings 85 and the following statement thereof.

The lever M is provided centrally thereof with a depending shoulder or projection m⁴, and in practice the arms g and g⁵ are turned around to the right or into the position occupied by the arm g⁵ in Figs. 1 and 2. In this position of said arms one of them will be held at each side of the shoulder or projection m⁴ of the lever M, and the sheets or leaves of music to be turned are connected with the spring-clamps L. When it is desired to turn the first leaf or sheet, the cord m² is pulled downwardly, and this releases the first arm or the arm g, and at the same time the shoulder or projection m⁴ descends and prevents the other from 90 passing out. When the cord m² is released, the last arm, g⁵, passes forwardly and is held by the hook m of the lever M, and whenever 95 it is desired to turn the sheet or leaf with 100

which this arm is connected it is only necessary to pull the cord m^2 , as in the first instance.

This device is simple in construction and 5 operation and is perfectly adapted to turn the sheets or leaves of music, and it is evident that my invention is not limited to the number of the pivoted arms g and g^5 , and any desired number thereof may be employed.

10 It is also apparent that changes in and modifications of the construction herein described may be made without departing from the spirit of my invention, and I reserve the right to make all such alterations therein 15 and modifications thereof as fairly come within the scope of the invention.

Having fully described my invention, I claim as new and desire to secure by Letters Patent—

20 1. A music holder and turner, comprising a base, a vertical standard secured thereto, a vertically-adjustable yoke mounted on said standard, a vertical arm connected with said yoke, a rod secured thereto, and extending 25 parallel with the base, outwardly-curved or segmental rods connected with the ends thereof, a plurality of spring-operated arms pivotally connected with said vertical arm, and adapted to swing between said outwardly- 30 curved rods, said arms being provided at their outer ends with spring-clamps, or other devices for holding sheets or leaves of music and a spring-operated lever pivotally connected with the upper outwardly-curved rod 35 at one end thereof, which is provided with two downwardly-directed projections or shoulders and which is adapted to operate, substantially as shown and described.

2. The herein-described music-holder, comprising a base A, a vertical standard B, connected therewith, a vertically-adjustable yoke b, provided with a set-screw b² mounted on the said standard, an angular rod D, having a depending arm d, by which the same is connected to the yoke, said rod being provided at its outer end with an upwardly-directed arm d², a rod E, secured to the outer end of said rod, two semicircular rods E² secured to said rod E, spring-clamps F secured to said rod E, a disk G mounted on the upwardly-directed arm d², an arm g, secured above said disk and having a circular head, g², a spiral spring g³ above said circular head, one end thereof being secured to said arm g, and the other to a standard g⁴, which is connected with the rod D, another arm g⁵ above the spring g³, a spring g⁶ above the arm g⁵ and connected therewith, and with the standard g⁴, the arm g⁵ being curved downwardly and extending parallel with the arm g, clamps L, 60 secured to the said arms g and g⁵, the lever M pivotally connected with the rod E², the inner end of said lever being provided with a hook m and the outer end having a depending cord m², and a spring m³, one end of which is connected with said lever and the other end with a rod E, all constructed and adapted to operate as set forth.

In testimony that I claim the foregoing as my invention I have signed my name, in presence of the subscribing witnesses, this 7th day of April, 1896.

FRED MITCHELL STACY.
